UNITED STATES PATENT OFFICE.

WILLIAM WEBSTER, OF SAN FRANCISCO, CALIFORNIA.

IMPROVEMENT IN BUNGS.

Specification forming part of Letters Patent No. 150,379, dated April 28, 1874; application filed February 28, 1874.

To all whom it may concern:

Be it known that I, WILLIAM WEBSTER, of San Francisco, in the county of San Francisco and State of California, have invented an Improved Bung for Barrels; and I do hereby declare that the following is a full, clear, and exact description of the same, reference being had to the annexed drawing, and to the letters marked thereon.

My invention relates to an improved bung for barrels; and it consists in a novel combination of a permanent bushing for the barrel with a bung and an improved method of securing the same so that it shall be tight, and at the same time easily removable at any time when necessary.

To more fully illustrate my invention, reference is had to the annexed drawing, in which Figure 1 is a sectional elevation, showing the bush and bung in place. Fig. 2 is a perspective view of the bung and nut. Fig. 3 is a bottom view of the bushing, showing the nut.

A is a bush of metal, which is screwed into the opening made in the barrel for that purpose. At the bottom or in side end of the bush is a flange, B, which contracts the opening, as shown. Two lugs, C C, project into the barrel from this flange, in a line parallel with the axis of the bushing, for the purpose of locking the bung when in place. The bung D is made small enough to pass into the bushing, and a leather washer, e, upon its under side rests upon the flange B when it is in place, and thus makes a tight joint. The upper part of the bung is so made as to receive a key or wrench, for the purpose of turning it when necessary. A screw, E, projects from the lower end of the bung, and a peculiar-shaped nut, F, fits the screw. This nut is smaller than the opening through flange B for the principal part of its circumference, but is provided with two lugs, g, at opposite sides, which can only pass through the opening in the bushing by turning the bung to one side.

It will be manifest, then, that when it has been pushed through and turned, so as to be straight again, the lugs g will rest against the lower side of the flange B.

The operation will be as follows: The bush A being screwed into the barrel, the bung is inserted by turning the nut F until it stands across, so that the head of the bung will turn enough to allow the nut to pass through the opening until it is below the flange B. Then, by turning the bung around, the nut will be drawn up against the bottom of the flange B, the lugs C preventing the nut from turning around.

The lower end of the lever may have a head to prevent the nut from coming off.

If desired, the lugs C may be formed inside the bushing, so that the nut F will be inside of the bush, and not project into the barrel.

In this case a square socket may be formed in the top of the bung, which will be flush with the top of the bushing. This socket serves to receive a key to loosen the nut when necessary to take out the bung.

By this construction I am enabled to make a bung which shall be tight, and at the same time easily removable.

Having thus described my invention, what I claim as new, and desire to secure by Letters Patent, is—

The bushing A, with its flange B and lugs C C, in combination with the bung D, with its screw-spindle E, and the nut F, with lugs g, constructed to operate substantially as and for the purpose herein described.

In witness whereof I have hereunto set my hand and seal.

WILLIAM WEBSTER. [L.S.]
